UNITED STATES PATENT OFFICE.

LOUIS ALPHONSE DE VILLERS, OF WINNIPEG, MANITOBA, CANADA.

BLIND ATTACHMENT.

1,333,906.

Specification of Letters Patent. Patented Mar. 16, 1920.

Application filed January 4, 1919. Serial No. 269,627.

To all whom it may concern:

Be it known that I, LOUIS ALPHONSE DE VILLERS, of the city of Winnipeg, in the Province of Manitoba, Canada, have invented certain new and useful Improvements in Blind Attachments, of which the following is the specification.

The invention relates to improvements in blind attachments and particularly to the attaching of a blind to a roller and the principal object of the invention is to provide an improved form of fastening which will automatically release to free the blind from the roller when the same has been extended or pulled off the roller the full length and by so doing prevent the destroying of the blind as occurs where the blind is permanently fastened to the roller.

A further object is to construct the attachment in a simple, easily applied and durable manner and so that it can be relied on to always do its work.

With the above objects in view the invention consists essentially in the arrangement and construction of parts hereinafter more particularly described and later pointed out in the appended claims, reference being had to the accompanying drawing in which:—

Figure 1 represents a portion of a window frame with a blind attached thereon.

Fig. 2 represents an enlarged vertical sectional view through a blind and roller with my attachment thereon and with the blind partially wound on the roller.

Fig. 3 represents a view similar to Fig. 2 with the blind extended or about pulled off the roller.

Fig. 4 represents a view similar to the preceding ones with the blind released.

Fig. 5 represents a plan view of the roller, certain parts being broken away to expose construction.

Fig. 6 represents a plan view of a fragmentary portion of the blind.

In the drawing like characters of reference indicate corresponding parts in the several figures.

1 represents a window frame provided with the usual brackets 2 and 3 which receive the customary end supports 4 and 5 of the blind roller 6. These parts, with the exception of certain changes in the roller, are of ordinary construction and are not herein more minutely described.

In the present instance the roller is shown

as a metal one comprising disk like ends or heads 7 which carry a cylindrical sheet metal body 8. 9 represents a lengthwise extending groove formed in the sheet metal body of the roller and having one of the side walls 10 thereof positioned more or less at an obtuse angle to the base 11 of the groove and the other side wall 12 curved to present what might be called a side extension or pocket 13 to the groove which lies behind an overhanging tongue 14. This groove or channel with its extension can be made by shaping the sheet forming the cylindrical body prior to mounting it on the heads 7.

The blind 15 which is mounted on this roller has the attaching end enlarged, this being accomplished in the present instance by turning the end of the blind back on itself and sewing down and then inserting a wire 16 in the hem so formed. The enlarged end of the blind is inserted in the pocket as best shown in Figs. 2 and 3 of the drawing and it is releasably secured in this position by the device now described.

17 represents an arched strip or plate 80 passing lengthwise of the roller and arched to lie flat on the roller. One edge of the plate is pivotally attached as at 18 to the body of the roller and when in place it is desirable to have the groove in the roller 85 lying more or less centrally underneath the plate. 19 represents a lengthwise extending clamping bar permanently secured to the inner side of the plate and adapted to enter the groove 9. This bar and plate form what 90 might be termed a releasable clamp for holding the blind to the roller. When it is desired to secure the blind to the roller the plate is swung out or away from the roller and the enlarged end of the blind is placed 95 in the pocket. The plate is then swung back to the original position and in this position the bar 19 is designed to enter the pocket and jam in between the edge of the tongue and the wall 10. Here however it is explained 100 that it must not jam in too tightly but just sufficiently to maintain its closed position under normal conditions. Once the fastening is made there will be a part of the blind caught between the plate and the roller. 105

With this fastening the blind can be adjusted in the ordinary way by pulling it up and down and in such adjustment it winds around the roller. However, should the circumstance arise where the blind is pulled 110

off unduly, it will automatically release itself from the roller, thereby preventing the tearing or other destruction of the blind. The releasing action is best disclosed by reference to Figs. 3 and 4. In Fig. 4 the blind is shown as practically all pulled off the roller. Any further pull on the blind has the effect of swinging the then lower edge of the plate 17 outwardly from the roller, thereby effecting the withdrawal of the bar from the groove and the release of the upper edge of the blind as it will here be obvious that upon the clamping plate being released the continued pulling of the blind will withdraw 15 the end of the blind from the pocket and free the blind without damage.

While I have described this invention as associated with a window blind, still I wish it to be understood that it can be applied 20 on any blind winding off and on a roller and where it is desired to have the blind automatically released from the roller when the blind is unduly unwound.

Further, while I have shown the invention 25 as utilized on a metal roller, still it will be readily understood that a wooden roller could be used and that in such an instance it would be only necessary to form the groove by channeling it out in the wood.

30 What I claim as my invention is:—

1. The combination with a roller and a blind, of a releasable clamp normally fastening the inner end of the blind to the roller and designed to be released by the pulled 35 blind at a time immediately prior to the blind being totally unwound from the roller.

2. The combination with a roller and a blind, of a swinging clamp normally clamping the inner end of the blind to the roller 40 and designed to be swung away from the roller by the action of the unwinding blind and to release the blind from the roller at

the time the blind is practically unwound from the roller.

3. In combination, a roller having a 45 lengthwise extending groove therein, a blind having the inner end entered within the groove, a clamping plate lying on the face of the roller and extending to opposite sides of the groove and covering a portion of the 50 inner end of the blind and a clamping bar attached to the plate and normally entering the groove and holding the blind normally fastened to the roller.

4. In combination, a roller having a 55 lengthwise extending groove formed therein, said groove having a side pocket, a blind having the attaching end enlarged and lying in the pocket, a plate lying on the roller and covering the groove and extending to the 60 sides of the groove and overlying the inserted end of the blind and a clamping bar carried by the plate and entering the groove and locking the enlarged end of the blind in the pocket.

5. In combination, a roller having a 65 lengthwise extending groove formed therein, said groove having a side pocket, a blind having the attaching end enlarged and lying in the pocket, a plate having one edge pivotally attached to the roller, said plate covering and extending across the groove and overlying at its free side the attached end 70 of the blind lying on the roller and a clamping bar secured to the plate and extending 75 within the groove and normally locking the enlarged end of the blind in the pocket.

Signed at Winnipeg, this 21 day of October, 1918.

LOUIS ALPHONSE DE VILLERS.

In the presence of:—

G. S. RYBURGH,
H. B. WAKEFIELD.
